UNITED STATES PATENT OFFICE.

JULIA FOERSTER, OF MANITOWOC, WISCONSIN.

BIB HOLDER.

Application filed May 16, 1924. Serial No. 713,790.

To all whom it may concern:

Be it known that I, JULIA FOERSTER, a citizen of the United States, residing at Manitowoc, in the county of Manitowoc and 5 State of Wisconsin, have invented certain new and useful Improvements in Bib Holders, of which the following is a specification.

The invention relates to bib holders for 10 children and particularly of the type adapted to be secured to a table.

A further object of the invention is to provide a clamp structure adapted to be secured to the edges of a table of either the 15 round or square type provided with a longitudinal pivoted clamp which is adapted to detachably secure the lower end of the bib to the table, the other end of the bib being adapted to be secured around the neck 20 of the wearer to thereby effectually prevent food or the like falling upon the floor or chair, or upon the clothes of the child.

A further object of the invention is to so form the parts of my device that the same 25 can be manufactured without material expense in view of its simplicity.

Other and more detailed objects of the invention will be apparent from a reading of the following description when considered 30 in conjunction with the drawing attached hereto and forming a part hereof, in which Figure 1 represents my device in elevation attached to the edge of a table: Figure 2 a plan view of my device attached to a table 35 with a straight edge top: Figure 3 a plan view of same attached to a round top table: Figure 4 a vertical cross sectional view of Figures 1 and 2.

Referring now more specifically to the 40 drawing, the table clamp consists of the longitudinal element 1 provided at its two extremities with integral U-shaped clamps 2 and 3, respectively, the other terminals 4 and 5 of which are co-extensive with the 45 inner edge of the longitudinal part 1 to thereby constitute an effectual bearing for the table 6 secured therebetween. It will be noted that by reason of this peculiar shape of the clamping element that the same can 50 be applied to either the round or square type of table in view of the open space between the U-shaped clamping fingers and the longitudinal element 1. In addition to constituting a bearing surface for the table

when the clamp is in operative position, the 55 longitudinal part 1 also is provided with up-turned flanges 7 and 8 having openings 9 and 10 therein to receive the pins 11 and 12 integral with and extending from the pivoted bib clamping. This pivoted bib holding 60 bar is provided with integral projecting teeth 13 for securely holding the lower end of the bib 14 between the same and the upper surface of the longitudinal part 1. The bib clamp is provided with a finger handle 65 15 whereby the same can be easily rotated into or out of engagement with the bib.

In order to apply my device to a table and to securely clamp the same thereto, I provide screw threaded members 16 and 17 for 70 engagement with corresponding screw threads located near the outer extremities of the U-shaped table clamps 2 and 3. To the outer ends of these screw threaded elements I attach concaved table engaging plates 18 75 and 19 which are adapted to firmly engage the end surface of the table when the screw threaded members have been sufficiently rotated. It will therefore be obvious that my device is capable of attachment to tables of 80 different diameters by reason of the aforesaid screw threaded clamping elements. Furthermore, the U-shaped clamps are made of spring material to permit a slight expansion of the same when it is desired to attach the device to furniture having an unusual diameter.

It will be apparent to those skilled in the art that many changes and arrangement 85 of parts, sizes, and the like can be made 90 without departing from the invention as expressed in the following claims.

Having thus described my invention, what I claim is:

1. A bib holder comprising a longitudinal element, U-shaped clamps provided at the outer extremities of said longitudinal element, means to secure said bib holder to supports having differential diameters and shapes, a rocking bib engaging member secured to said holder for detachable engagement with the end of the bib placed between said longitudinal element, substantially as described.

2. A bib holder provided with a longitudinal flat element for engagement with the top of a table, U-shaped clamps integral with said longitudinal element, the outer

edges of said clamps being substantially co-extensive with the outer edge of said longitudinal element to receive the edge of a table therebetween, adjustable devices for securing said clamp to the table, said longitudinal member being provided with integral up-standing lugs at the extremities

thereof, a pivoted bib engaging bar secured to said lugs and adapted to detachably engage the end of a bib, substantially as described. ¹⁰

In testimony whereof I affix my signature.

JULIA FOERSTER.
